WRESTLING TIMER OR THE LIKE

Claude P. Baumann, Upper Saddle River, N.J., assignor to Aristo Import Co., Inc., New York, N.Y., a corporation of New York

Filed July 16, 1969, Ser. No. 18,214

Term of patent 14 years

Int. Cl. D10—05

U.S. Cl. D42—7

FIG. 1.

FIG. 2.

FIG. 3.

FIG. 4.

FIG. 5.

FIG. 1 is a front elevational view of a wrestling timer or the like showing my new design;

FIG. 2 is a right side elevational view;

FIG. 3 is a rear elevational view;

FIG. 4 is a left side elevational view; and

FIG. 5 is a top plan view.

The face of the timer is lined to indicate contrast of color, without reference to specific colors.

I claim:

The ornamental design for a wrestling timer or the like, substantially as shown and described.
